UNITED STATES PATENT OFFICE.

GILBERT F. HELSON, OF RICHMOND, NEW YORK, ASSIGNOR TO E. R. DURKEE AND COMPANY, OF NEW YORK, N. Y., A FIRM.

WRAPPING-MACHINE.

1,255,605.

Specification of Letters Patent.

Patented Feb. 5, 1918.

Application filed August 9, 1917. Serial No. 185,275.

To all whom it may concern:

Be it known that I, GILBERT F. HELSON, a subject of the King of Great Britain, but having declared my intentions of becoming 5 a citizen of the United States, residing at the borough of Richmond, in the county of Richmond, city and State of New York, have invented an Improvement in Wrapping-Machines, of which the following is 10 a specification.

My invention relates to machines for placing wrappers upon bottles, cans, or other cylindrical articles, and the present application particularly relates to means for rolling 15 the wrappers around the articles, folding the ends of the wrappers over the ends of the articles, carrying the wrapped articles forward and delivering the same to a receptacle provided therefor. This application 20 is a division of my application Serial No. 151,397, filed by me February 28, 1917, which relates to the mechanism for feeding the wrappers to the bed of the machine in the path of the wrapping block described 25 and claimed herein.

In the same machine I make use of mechanism for feeding the bottles or other cylindrical articles to the machine and elevating them one at a time to the bed of the machine 30 adjacent the wrapper deposited thereon by the mechanism forming the subject matter of my said application Serial No. 151,397, which bottle feeding and elevating mechanism forms the subject matter of still another division of my said application Serial 35 No. 151,397 which other divisional application was filed Aug. 9, 1917, under Serial No. 185,276.

In the accompanying drawings:

40 Figure 1 is a plan view of my improved machine.

Fig. 2 is a side elevation partly in section.

45 Fig. 3 is a rear view of the wrapping block detached.

Fig. 4 is a detail sectional view on the broken line 4—4 of Fig. 1 of the bottle gripping arms, and

50 Fig. 5 is an inverted plan view of the wrapping block.

Similar reference numerals denote like parts throughout the several views.

The frame of the machine is approximately rectangular and comprises a plural-

ity of uprights such as 10 and 11, the top 55 being stepped, forming a main bed 12, extending longitudinally the full length of the frame at its front, and a lower bed 13, at the rear, upon which are supported a paste or glue box 14, and a feed box or holder 15, 60 for the wrappers.

16, indicates the main shaft which is journaled at its respective ends in cross beams 17.

18, designates the motor, upon the shaft 19, on which is secured a gear 20, meshing 65 with gear 21, fixed to a shaft 22, journaled in bearings in a bracket 23 fixed to the frame at the front of the machine in line with the main shaft.

Fixed to the shaft 22, at one side of the 70 gear 21, is a pulley 24. 25, indicates a pulley fixed to the main shaft 16, adjacent one end. 26, denotes the drive belt which passes around the pulleys 24 and 25.

The wrappers, one at a time, in rapid succession are glued along two or more edges, taken from the holder 15, and deposited upon the main bed 12, by the wrapper carrier 27, and connected release plate 28, constructed and operated by mechanism described and 75 illustrated in my said application Serial No. 151,397.

There is an opening 29, in the main bed 12, adjacent the place at which the wrappers are deposited by said carrier and release 85 plate.

A plurality of bottles 30, which are to be covered by the wrappers, are arranged in a row within a feed chute 31, the bottles being placed upon their sides, bottoms foremost, 90 the top of one bottle contacting with the bottom of the next bottle. The bottles are pushed toward the open end of the chute 31 under the bed 12, the length of one bottle at a time by the pusher 32 operated by a cam 33 95 keyed to the main shaft 16, which acts upon a roller 34 attached to an arm 35, one end of which is bifurcated and straddles the main shaft, the other end of the arm being pivotally connected to a lever 36 fulcrumed upon a bifurcated lug 37, secured to the cross beam 38 the other end of the lever being pivotally connected to one end of a connection rod 39, the other end of which is connected with the pusher 32.

When one of the bottles is pushed out of the open end of the chute 31, it is deposited upon a bed 40, which is secured to a block 41,

and to this block the upper end of an arm 42, is pivotally connected. The lower end of said arm is bifurcated and straddles the main shaft. A roller 43, attached to one side 5 of said arm is acted upon by a cam 44 keyed to the main shaft whereby the block and bed are raised into the opening 29 in the bed 12 of the machine. This bottle feeding and elevating mechanism forms the subject matter 10 of my other divisional application above referred to, filed August 9, 1917, under Serial No. 185,276.

A bottle reaches the top of the main bed 12 just as a glued wrapper has been deposited upon the bed in front of the opening 29 by the wrapper carrier 27 and release plate 28 fully described and illustrated in my said application Serial No. 151,397.

45, indicates a vertical shaft journaled at 20 its lower end in a bracket 46, its upper end passing through and journaled in a bearing 47, in an extension of the frame of the bed 13. Keyed to the upper projecting end of the shaft 45 is a horizontal gear 48. 49, is 25 another horizontal gear keyed to the lower end of the shaft 45 and meshing with a gear 50 keyed to the main shaft 16.

51, is a short vertical shaft passing through an opening in the bed frame 13, and bearing 30 52, its lower end being threaded upon which is screwed a nut 53. Upon the upper end of the vertical shaft 51 there is keyed a gear 54 meshing with the gear 48 on the shaft 45.

55, designates a vertical shaft the lower 35 end of which is journaled in the cross beam 38, its upper end passing through an opening in the bed 12, there being a bearing 56 for this shaft secured upon the under side of the bed 12.

40 A gear 57 is secured upon the shaft 55 which gear meshes with the gear 54 on the shaft 51. By this gear connection it will be seen that the shaft 55 is continuously revolved while the main shaft is rotating.

45 58 indicates a hub keyed to the upper end of the shaft 55 from the upper end of which hub projects two horizontal arms 59 and 60, the free ends of which are spaced apart a predetermined distance, there being a cross 50 brace 61 between the two arms, and side braces 62 and 63 extending from the lower part of the hub 58 and connecting with the arms 59 and 60 respectively at a predetermined distance from their free ends.

55 The hub 58, arms 59, and 60, cross brace 61, and side braces 62 and 63, are preferably cast in one piece of metal.

64, indicates the wrapping-block which is curved longitudinally and preferably covered on its under surface with soft material or a pad 65.

66 and 67, indicate two hangers, the lower ends of which are pivotally connected to the wrapper-block, one at each side thereof adjacent one end, The upper ends of these

hangers are pivotally connected to the free end of the arm 59, by a bolt 68.

Each of these hangers is preferably composed of two rods provided with right and left screw threads respectively upon which 70 is screwed a turnbuckle or threaded sleeve 69, by means of which the height of the wrapping-block above the pad 73 on the bed 12 may be adjusted.

70 and 71, indicate another pair of hangers 75 similar to the hangers 66 and 67. 72, is an angle piece which is secured to the end of the arm 60 by a bolt 74, which bolt also pivotally connects the upper ends of the hangers 70 and 71 to the end of the arm 60. 80 A lug 75 provided with a hole is secured to the top of the wrapper-block 64 and the lower end of the hanger 70 is pivotally secured thereto by a bolt. The opening in the bottom of the hanger 70 for the passage of 85 said bolt is elongated somewhat vertically to allow a certain amount of vertical movement to that end of the wrapper-block which is controlled by a spiral spring 76 which surrounds a vertical pin 77 secured at its 90 lower end to the top of the wrapper-block, its upper end extending through a hole in the angle-piece 72, the spring 76 bearing at its top against the under surface of the angle-piece and at its bottom against the 95 top of the wrapper-block.

78 and 79, denote two connecting devices between the respective side braces 62 and 63, and the wrapping-block 64. These connections are constructed similar to the hangers 100 66 and 67; that is, they are each formed of two sections of rod provided with right and left threads respectively upon which are screwed turnbuckles or right and left internally threaded sleeves 80.

One end of the connection 78 is pivotally connected to the wrapping-block, the other end being pivotally connected to the outer side of the brace 62. The connection 79 is connected at one end pivotally to the lug 75, 110 upon the top of the wrapper-block and its other end is pivotally connected to the outer side of the brace 63. These connections 78 and 79 provide means for adjusting and holding the wrapping-block in an inclined relation to the bed 12 when so desired and as shown, although it will be seen that the wrapping-block may be positioned so that its bottom surface will be parallel with the bed.

Upon the rear end of the wrapping-block 64 and secured thereto is a vertical cross-piece 81, one end of which extends a predetermined distance beyond the inner side of the wrapping-block.

82 and 83 are two gripper arms pivotally connected to the inner side of the cross-piece 81.

The arm 83 is pivoted at 84 and extends along the inner surface of the cross-piece 130

beyond each end thereof, that end at the outer end of the cross-piece being bent downwardly at right angles adjacent the outer side of the wrapping-block 64.

5 The arm 82 is pivoted at a point on the cross-piece lower than the pivot 84, and extends from that point along the inner surface of the cross-piece and beyond its inner end. Adjacent its pivotal connection this 10 arm 82 is bent downwardly at right angles adjacent the inner side of the wrapping-block. Upon the inner sides of each of the downwardly bent portions of the arms 82 and 83 and at the ends thereof, is secured 15 a pad 85 by any suitable means. I have shown rivets 86 for this purpose.

The inner ends of the arms 82 and 83 are enlarged in thickness and upon their opposite surfaces are each provided with a socket 20 87, in each of which is positioned an elongated roller 88 provided with trunnions 89 having bearings at the opposite ends of said sockets.

The peripheries of these rollers project 25 slightly outside the sockets.

The horizontal portions of the gripper arms are normally held parallel to each other by a spiral spring 90, one end of which is fastened to the arm 82 and its other end 30 fastened to the arm 83.

Upon each side of the wrapping-block 64 forward of the gripping arms, are a plurality of depending folding fingers 91, secured to the sides of the block at their upper ends by rivets or screws 92. These rows 35 of folding fingers extend only a predetermined distance along the rear end of the wrapping-block.

93, denotes a semi-circular spreader-rail 40 supported a predetermined distance above the bed 12 by vertical posts 94, secured at their upper ends to the rail and at their lower ends to the top of the bed 12. The ends of this rail are beveled.

45 The vertical shaft 55, being continuously revolved by the mechanism heretofore described so long as the main shaft 16 is being driven by the motor 18, the wrapping-block is continuously carried in a circle 50 over the bed 12 at an adjusted height above the same, and when its forward end, which is preferably curved slightly upwardly, comes in contact with the periphery of a bottle which has been raised by the elevating

55 means before referred to to the top of the bed 12, it rolls the bottle forward over the gummed wrapper (which has been deposited upon the pad 73 by the means and in the manner hereinbefore referred to,) and in so 60 doing the wrapper is rolled around the bottle and secured thereto by its gummed edge longitudinally of the bottle; this is accomplished instantaneously and before the bottle reaches the folding fingers 91, but in 65 passing these folding fingers that portion of

the rolled wrapper extending from each end of the wrapped bottle is turned over and down upon the top and bottom of the bottle by such folding fingers. When past the row of folding fingers the bottle has been 70 rolled into a position between the gripper arms 82 and 83 at either side of the block 64, and the movement of the wrapper-block is so timed that at this moment the inner horizontal ends of the gripper arms 75 have reached one end of the spreader rail 93, which passes between the rollers 88 in the gripper arms spreading them apart and throwing their padded ends toward each other and against the top and bottom of the 80 wrapped bottle thus gripping the same between them, (see Fig. 4) and carrying it forward until the rollers 88 pass off the rail 93 at its other end when the arms 82 and 83 are drawn back to their normal position by 85 the contracting of the spring 90.

When the wrapped bottle is released from the gripper arms it drops through an opening 95 in the bed 12, and into a curved inclined chute 96 arranged under the bed 12 90 at this point, and from the chute 96 the wrapped bottle is deposited in an upright position upon a conveyer band 97. A guide piece 98 is arranged at the lower open end of the chute 96 to set the wrapped bottles upright as they are delivered from the chute and upon the conveyer.

I prefer to provide a stop 99 at the forward end of the opening 95 in the bed to prevent any possibility of any of the 100 wrapped bottles passing or striking the edge of the opening.

The movements of the respective parts are so timed that a gummed wrapper will be deposited upon the pad of the bed, and a bottle elevated to the level of the bed so as to be in the path of the wrapping block at each revolution of the same. The machine is operated with accuracy and rapidity, and is adjustable to varying sizes and styles of 110 cylindrical articles.

A semi-circular shield 100, is preferably provided for the protection of the operator against contact with the moving parts over the bed, and I also prefer to employ a covering 115 101, for that part of the machine below the bed.

I claim as my invention:

1. In a wrapping machine, in combination with a frame and bed supported thereby, 120 a wrapping-block adjustably supported over the top of the bed at a height to contact with the periphery of the article to be wrapped, and means for moving said block in a circle.

2. In a wrapping machine, in combination with a frame and bed supported thereby, a wrapping-block adjustably supported above the top of the bed at a height to contact with the periphery of the article to be wrapped, a plurality of folding fingers at- 125 130

tached to said block on opposite sides thereof, and means for moving said block in a circle over the top of the bed.

3. In a wrapping machine, in combination 5 with a frame and bed supported thereby, a wrapping-block adjustably supported above the top of the bed at a height to contact with the periphery of the article to be wrapped, a plurality of folding fingers attached to 10 said block on opposite sides thereof, gripper arms carried by said block at one end thereof, and means for moving said block in a circle over the top of the bed.

4. In a wrapping machine, in combination 15 with a frame and bed supported thereby, means for depositing a wrapper upon said bed, means for placing an article to be wrapped adjacent one edge of the wrapper so deposited, a wrapping-block adjustably 20 supported above the bed at a height to contact with the periphery of the article so placed, and means for moving said block in a circle.

5. In a wrapping machine, in combination 25 with a frame and bed supported thereby, means for depositing a wrapper upon said bed, means for placing an article to be wrapped adjacent one edge of the wrapper so deposited, a wrapping-block adjustably 30 supported above the bed at a height to contact with the periphery of the article so placed, a plurality of folding fingers attached to said block on opposite sides thereof, and means for moving said block in a 35 circle over the top of the bed.

6. In a wrapping machine, in combination 40 with a frame and bed supported thereby, means for depositing a wrapper upon said bed, means for placing an article to be wrapped adjacent one edge of the wrapper so deposited, a wrapping-block adjustably 45 supported above the bed at a height to contact with the periphery of the article so placed, a plurality of folding-fingers attached to said block on opposite sides thereof, gripper arms carried by said block, means for moving said block in a circle over the top of the bed, and means for operating 50 said gripper arms.

7. In a wrapping machine, in combination 55 with a frame and bed supported thereby, a vertical shaft extending through an opening in the bed, a gear keyed to said shaft, a hub keyed to the upper end of said shaft and having projecting arms, a wrapping block, adjustable hangers connecting said block with said arms, a drive shaft, a gear keyed thereon, and intermediate gearing connecting said gear with the gear on said vertical shaft and by means of which said

wrapping-block is carried in a circle over the bed.

8. In a wrapping machine, in combination with a frame and bed supported thereby, a vertical shaft extending through an opening 65 in the bed, a gear keyed to said shaft, a hub secured to the upper end of said shaft and having projecting arms, a wrapping block, adjustable hangers connecting said block with said arms, a plurality of 70 folding fingers attached to said block on opposite sides thereof, a drive shaft, a gear keyed thereon, and intermediate gearing connecting said gear with the gear on said vertical shaft and by means of which said 75 wrapping block is carried in a circle over the top of the bed.

9. In a wrapping machine, in combination with a frame and bed supported thereby, a vertical shaft extending through an opening 80 in the bed, a gear keyed to said shaft, a hub secured to the upper end of said shaft and having projecting arms, a wrapping-block, adjustable hangers connecting said block with said arms, a plurality of folding-fingers 85 attached to said block on opposite sides thereof, gripper arms carried by said block, a drive shaft, a gear keyed thereon, intermediate gearing connecting said gear with the gear on said vertical shaft and by 90 means of which said wrapping block is carried in a circle over the top of the bed, and means for operating said gripper arms at predetermined points during the movement of said block.

10. In a wrapping machine, in combination 95 with a frame and bed supported thereby, means for depositing a wrapper upon said bed, means for placing an article to be wrapped adjacent one edge of the wrapper 100 so deposited, a wrapping-block adjustably supported above the bed at a height to contact with the periphery of the article so placed, a plurality of folding fingers attached to said block on opposite sides thereof, a pair of gripper arms pivotally attached to the rear end of said block and having parallel branches projecting beyond the inner side of the block provided with facing rollers, means for moving said wrapping-block in a circle over the top of the bed, and a semi-circular spreader rail supported upon the top of the bed with which said rollers carried by said gripper arms engage, causing said arms to grip a wrapped 111 article and carry it forward and to release such grip as said rollers pass off the end of said rail.

Signed by me this 1st day of August 1917.
GILBERT F. HELSON.
